UNITED STATES PATENT OFFICE.

BERNHARD HANSEN, OF PARKWATER, WASHINGTON, ASSIGNOR OF ONE-HALF TO JOHN L. WYNN, OF SPOKANE, WASHINGTON.

FEED-WATER HEATER.

1,325,289.

Specification of Letters Patent.

Patented Dec. 16, 1919.

Application filed March 20, 1918. Serial No. 223,507.

To all whom it may concern:

Be it known that I, BERNHARD HANSEN, a citizen of Norway, (first papers taken out in the United States,) residing at Parkwater, in the county of Spokane and State of Washington, have invented certain new and useful Improvements in Feed-Water Heaters, of which the following is a specification.

- 10 The present invention relates to improvements in feed water heaters, for boilers, of the type generally adapted for use with locomotive boilers, and heated by the gases of combustion in the furnace.
- 15 The primary object of the invention is the provision of a simple but efficient device for this purpose that is applicable for use in the boiler furnace and that may be attached or detached when necessary, with 20 facility and despatch, and which will require a minimum amount of change in the boiler when such boiler is being equipped with the heater. The invention consists in certain 25 novel combinations and arrangements of parts with which the boiler furnace is equipped, including the reservoir or receiving receptacle and heater, and also in the manner and construction for connecting the members forming parts of the invention 30 with the furnace and flues of the boiler.

In the accompanying drawings one complete example of the physical embodiment of the invention is illustrated according to the best mode so far devised for the practical application of the principles of the invention.

Figure 1 is a longitudinal, vertical section of the boiler portion of a locomotive sufficient to illustrate the equipment there- 40 with of the device.

Fig. 2 is a section on line 2—2 of Fig. 1.

Fig. 3 is an enlarged, detail sectional view illustrating the manner of attaching the heater to the back head and back sheet 45 of the boiler furnace.

In the preferred embodiment of the invention as illustrated in the drawings sufficient of the structure of the boiler and furnace have been shown to illustrate the applicability of the invention, and the usual furnace A, roof sheet B of the boiler, fire opening C to the furnace, and grate D are all of well known construction. The back head E and back sheet F of the fire box 50 are utilized for the attachment of the heater

which is located in the furnace directly below the crown sheet G which is suspended by the usual stay bolts H. One of the fire tubes T of the boiler is omitted or changed as it passes through the tube sheet I, and 60 the usual form of brick arch J is located in usual position.

In equipping the boiler furnace with the heater of the present invention, the reservoir 1 and heater unit 2 are located beneath the 65 crown sheet and extend between the tube sheet and back sheet of the fire box. The reservoir is of sufficient size for the purpose and comprises a rectangular box of metal extending horizontally across the furnace 70 adjacent the back sheet F and above the fire opening C, and the reservoir is preferably fashioned with legs 1^a for engagement with the face of the back sheet for holding the reservoir stable.

The usual equipment for feeding water to the boiler is utilized, and the pipe 3 which leads from the usual injector, has the customary water check valve 4, and is connected to the reservoir by a short pipe 5 supported between the back head E and back sheet F of the furnace and a second branch pipe 5' forming an extension of the pipe 5 and connecting the back sheet with the reservoir. The two pipes as well as the 80 reservoir and heater, are supported directly from an attaching plate 6 which is secured to the back sheet F by the bolts 7 which pass through the plate, the back head and back sheet, and also secure the check valve 90 of the water feed pipe to the outside face of the back head.

The joint between the two pipes 5 and 5' is completed by the utilization of the thimble or sleeve 8, which forms an integral 95 part of the plate 6 and is seated, with a tapering fit, in an opening in the back sheet of the furnace, and it will readily be seen that the bolts 7 will hold the plate and its sleeve in rigid position on the back sheet. 100 Stay bolts 9 are threaded into the plate 6 and reservoir wall and these bolts hold the reservoir and heater in position in the furnace.

The heater unit 2 and its central pipe 2' 105 are centrally located below the crown sheet, the connection with the reservoir being indicated at 10, and at the front end the feed water heater is connected at 11 to a pipe 12 which is supported in the tube sheet, and 110

one of the flues is omitted from the fire flues to make room for this water pipe which delivers the heated water into the boiler approximately three or four feet from the rear 5 end of the flues.

The heater proper is of rectangular form with rounded ends, and the central branch 2' and parallel side members or pipes form an open device through which the gases of 10 combustion may be permitted to pass without obstruction therefrom, and in the passage of these gases the water in the heating device is heated preparatory to flowing to the boiler through pipe 12.

15 The reservoir is attached to the back sheet of the furnace through the instrumentality of the two attaching plates 6 and 6' and the water is fed directly into the reservoir and thence to the heating unit, being distributed

through the three branches of the unit in 20 order to enhance the heating capacity of the unit.

Claim:

The combination in a feed water heater with the back head of a boiler and back 25 sheet of the furnace, of a reservoir, a pair of alined water inlet pipes extending through the back head from the water inlet pipe, through the back sheet and opening into the reservoir, an attaching plate for 30 supporting the reservoir and pipes and connected with the reservoir and fixed to the inner wall of the back sheet, and an integral, internally threaded sleeve on the plate seated in an opening in the back sheet and 35 joining the two alined pipes.

In testimony whereof I affix my signature.
BERNHARD HANSEN.
